gammas per kilogram of my hydroxyethyl compound causes the same blood pressure rise as 1 to 2 gamma per kg. of epinephrine). When injected into the intact guinea pig, this group of compounds protects the animal from the asthma normally caused by histamine spray and therefore functions as bronchodilators in the intact animal as well as in the excised lung. Thus, they exhibit potent bronchodilator and vasodilator properties.

Examples of the hydroxy-alkyl compounds which have been synthesized and exhibit the above properties are:

wherein R is:

The group of compounds wherein R is a cycloalkyl-alkyl are quite different from Isuprel in structure but have several times its bronchodilator and peripheral vasodilator activity.

Examples of the cycloalkyl-alkyl compounds which have been synthesized are:

wherein R is:

The compounds wherein R is an aryl-alkyl group are also quite different from "Isuprel" in structure but have greater bronchodilator and peripheral vasodilator activity, as is aptly illustrated in the Biological Activity table of some of the compounds, below.

	R	Broncho-dilator Activity**
The new aryl-alkyl compounds.	(2-(1-phenyl-propyl))	*3
Isuprel.	(2-(4-phenyl-butyl))	*3
Isuprel.	(2-(1-p-methoxyphenyl-propyl))	0.6
Isuprel.	(2-(1-m,p-methylenedioxy-phenyl))	0.8

*NOTE.—The starred compounds are of interest in that they are more active as bronchodilator agents than would first appear from the table. According to the data listed here these compounds have about $\frac{1}{4}$ the bronchodilator activity of Isuprel; however, when tested at lower concentration and when compared at 25% relaxation of the bronchial musculature, as measured by perfusion flow, they are equally as potent and perhaps even more potent than Isuprel. They cause less depression of blood pressure in the cat than does Isuprel, and protect the intact guinea pig from asthma induced by histamine spray.

**NOTE.—The bronchodilator activity is evaluated by measuring the rate of flow of perfusion fluid through an excised guinea pig lung. The lung is constricted with histamine to simulate what occurs in an asthmatic attack. On perfusion of fluid containing the substance to be tested, the lung is relaxed. The figures in the table give the amount of compound in gammas (one gamma is $\frac{1}{1000}$ mg.) required to restore the flow to normal. Therefore, the lower the figure, the more active is the drug.

Examples of the compounds in this group which have been synthesized are:

wherein R is:

1-(1-phenyl-ethyl)

1-(2-phenyl-ethyl)

1-(3-phenyl-propyl)

2-(1-phenyl-propyl)

1-(2-phenyl-propyl)

2-(4-phenyl-butyl)

2-(1-p-methoxyphenyl-propyl)

2-(1-o-chlorophenyl-propyl)

2-(1-m,p-methylenedioxy-phenyl)

Experiments on compounds wherein R is a heterocyclic alkyl indicate that they are as active as epinephrine in bronchodilator tests. However, they produce blood pressure lowering in animals whereas epinephrine raises the blood pressure. Thus, they do not have this undesirable side effect of epinephrine. An example of this group of compounds which I have synthesized is:

Typical examples illustrating the preparation of my new compounds and their ketones are:

EXAMPLE I

Preparation of α -(3,4-dihydroxyphenyl)- β -(N-(4-methyl-2-pentyl)-aminoethanol) hydrochloride having the structural formula:

57 g. (0.48 mole) of 4-methyl-2-aminopentane was dissolved in 125 cc. of 60% ethyl alcohol. 150 cc. of ethyl alcohol containing 30 g. (.16 mole) of chloracetyl catechol was slowly added to this solution over a two hour period while stirring at reflux temperature. An inert atmosphere was maintained by bubbling nitrogen through the solution. The reaction mixture was stirred and refluxed for an additional four hours, cooled and acidified with HCl-gas to pH=2. On standing, a crystalline amino ketone precipitate formed which was filtered in an atmosphere of carbon dioxide and washed repeatedly with acetone. An alcoholic solution of 6.2 g. (0.2 mole) of this amino ketone precipitate was reduced with 1.0 g. of a 10% palladium-on-charcoal catalyst at a pressure of 60 lbs. of hydrogen. The reaction mixture was clarified by filtration in an atmosphere of carbon dioxide and concentrated to dryness by distillation in vacuo. The residual oil crystallized when suspended in anhydrous ethyl ether and 5.0 g. of a white precipitate was collected by filtration. This solid was purified by suspending it in 10 cc. of ice cold acetone and then collected by filtration, giving a yield of the desired compound of 3.1 g. (74%) and having a melting point of 123-125° dec.

EXAMPLE II

Preparation of α -(3,4-dihydroxyphenyl)- β -N-(4-methyl-2-hexyl)-aminoethanol hydrochloride having the structural formula:

33.0 g. (0.17 mole) of chloracetyl catechol was dissolved in 150 cc. of ethyl alcohol. 80 cc. of 60% ethyl alcohol, containing 60 g. (.52 mole) of 4-methyl-2-hexyl-amino was slowly added to this solution over a period of two hours while maintaining the reaction mixture at reflux temperature and stirring. Stirring and refluxing were continued for another four hours. The solution was then cooled, acidified with concentrated aqueous hydrochloric acid and then concentrated to viscous consistency by distillation in vacuo. The residue was dissolved in 250 cc. of methylethylketone and allowed to stand. The amino-ketone crystalline precipitate which formed was filtered, washed with methylethylketone, resuspended in 100 cc. of fresh methylethylketone, filtered and then recrystallized from 120 cc. of isopropyl alcohol. An alcoholic solution containing 8 g. (0.25 mole) of these aminoketone crystals was then reduced with .1 gm. of platinum oxide (PtO_2) at a pressure of 60 lbs. of hydrogen. The reaction mixture was filtered and the filtrate concentrated to dryness in vacuo. The oily residue was dissolved in water and the aqueous solution neutralized with 4 g. of sodium bicarbonate. The resultant gummy precipitate was extracted from the aqueous phase with n-butyl alcohol and then acidified with glacial acetic acid, (about 3 cc.). This solution was then concentrated to dryness in vacuo and the residue crystallized from 60 cc.

of acetone giving a yield of the desired compound of 6 g. (75%) which has a melting point of 136-137° dec.

EXAMPLE III

Preparation of α -(3,4-dihydroxyphenyl)- β -(N-2-hydroxyethyl)-aminoethanol hydrochloride having the structural formula:

10 A mixture of 2-hydroxyethylamine [18.3 g. (0.30 mole)], chloracetyl catechol [18.5 g. (0.10 mole)] and 60% ethanol (100 cc.) was stirred at room temperature for three hours, cooled, acidified with 20 cc. of concentrated HCl and then concentrated in vacuo until crystals formed. 15 The residual mixture was cooled, filtered and immediately suspended in boiling isopropyl alcohol (60 cc.). After cooling and filtering, the 7.5 g. of this aminoketone of the desired antispasmodic compound was dissolved in water and subjected to hydrogenation with .2 g. of PtO_2 at 60 lbs. of hydrogen. The hydrogenation mixture was filtered, concentrated to dryness in vacuo and crystallized from acetone-isopropanol. Recrystallization from absolute ethanol gave a yield of the desired anti-spasmodic compound of 2.7 g. which melted at 116-117° dec.

EXAMPLE IV

Preparation of α -(3,4-dihydroxyphenyl)- β -N-(cyclohexylmethyl)-aminoethanol hydrochloride having the structural formula:

35 A mixture of chloracetyl catechol [13.0 g. (0.07 mole)], cyclohexylmethylamine [22.0 g. (0.20 mole)], and 130 cc. of 60% ethanol was stirred and refluxed for two hours, cooled, acidified with 15 cc. of concentrated aqueous hydrochloric acid and then allowed to stand at room temperature for three days. The crystalline aminoketone precipitate which formed was filtered, washed with 1:1 acetone: ethanol and then acetone. A 50% alcoholic solution of 8 g. (.027 mole), of this aminoketone precipitate was reduced with .2 g. PtO_2 at 60 lbs. of hydrogen, clarified by filtration and concentrated to dryness in vacuo. The residue was dissolved in 60 cc. of hot acetone and the solution allowed to stand for approximately two days. The antispasmodic crystalline precipitate which formed was filtered giving a yield of 5.8 g. (72%) and had a melting point of 151-152° dec.

EXAMPLE V

60 Preparation of α -(3,4-dihydroxyphenyl)- β -(N-2-phenylisopropyl) aminoethanol hydrochloride having the structural formula:

65 An alcoholic solution of 18.5 g. (0.10 mole) of chloracetyl catechol was added to 40.5 g. (0.30 mole) of phenylisopropylamine dissolved in 60 cc. of 60% ethanol at reflux temperature and with continual stirring. Stirring and refluxing were continued for another five hours after which the reaction mixture was cooled and then acidified with 20 cc. of concentrated aqueous HCl. The

acid solution was concentrated in vacuo to a viscous consistency and the residue dissolved in acetone. On standing, the aminoketone of the desired antispasmodic component precipitated and was filtered. The filtrate was dissolved in isopropyl alcohol and permitted to recrystallize. An alcoholic solution of 8.6 g. (.027 mole) of this aminoketone precipitate was reduced with .3 g. PtO_2 at 60 lbs. of hydrogen, clarified by filtration, concentrated to dryness in vacuo and the residue crystallized from acetone giving a yield of the desired antispasmodic of 7.0 g. (80%) which had a melting point of 139-140° dec.

EXAMPLE VI

Preparation of α - (3,4 - dihydroxyphenyl) - β - (N-2 - p - methoxyphenyl - isopropyl) - aminoethanol hydrochloride having the structural formula:

A mixture of p-methoxyphenylisopropylamine [50.0 g. (0.30 mole)], chloroacetylcatechol [18.5 g. (0.10 mole)], and 80 cc. of 60% ethanol was stirred and heated at 60° for 6 hours. The reaction mixture was acidified with concentrated HCl and concentrated to a viscous consistency in vacuo. The aminoketone residue was suspended in hot isopropyl alcohol and filtered. This aminoketone filtrate was then reduced with platinum oxide in the same manner as that employed in the previous examples. The residue after concentration was crystallized from acetone giving a 60% yield of the desired compound which had a melting point of 122-123° dec.

EXAMPLE VII

Preparation of α - (3,4 - dihydroxyphenyl) - β - N-(α -2-furylisopropyl)-aminoethanol hydrochloride having the structural formula:

24.0 g. (0.13 mole) of chloroacetylcatechol was added to 50.0 g. (0.40 mole) of 2-furylisopropylamine dissolved in 80 cc. of 60% ethanol over a period of two hours while stirring continually and maintaining a temperature of 60°. Stirring at a temperature of 60° was continued for another two hours. The reaction mixture was then cooled and the pH adjusted to 4 with 21 cc. of concentrated HCl. The acid solution was concentrated to dryness in vacuo and the residue crystallized from 800 cc. of isopropyl alcohol. Five gm. of these aminoketone crystals was reduced in absolute alcohol with platinum oxide at 60 lbs. of hydrogen, concentrated to dryness in vacuo and the residue rubbed under anhydrous ether until crystalline. The desired product was filtered under anhydrous conditions giving a yield of 4.3 g. (86%) which had a melting point of 70° dec.

In the above examples hydrochlorides of the desired compounds were produced. Those skilled in the art can use well known standard techniques for reducing these chlorides.

Listed in the two following tables are the compounds and their accompanying ketones which I have synthesized.

Table I

¹ Too hygroscopic.

In normal clinical use, the compounds will be employed in salt form and it is to be understood that the claims hereof cover the salts as well as the fundamental compounds. The activity of the compounds is independent of whether they are in salt form or otherwise. Salts may be prepared by any of the well-known standard methods. While the salt normally employed is the hydrochloride, I have prepared the compounds in the form of other salts such as acetate, sulfate and tartrate.

This application is related to my application Serial No. 469,305, filed November 16, 1954, and is a continuation-in-part of my application Serial No. 230,249, filed June 6, 1951, both of which applications are now abandoned.

Having described my invention as related to the embodiment described herein, it is my intention that the invention be not limited by any of the details of description unless otherwise specified, but rather be construed broadly within its spirit and scope as set out in the accompanying claims.

I claim:

1. A composition of the formula

wherein R is a hydroxyethyl group of the formula

35 2. A composition of the formula

wherein R is a hydroxypropyl group of the formula

UNITED STATES PATENT OFFICE
Certificate of Correction

Patent No. 2,900,415

John H. Biel

August 18, 1959

It is hereby certified that error appears in the printed specification of the above numbered patent requiring correction and that the said Letters Patent should read as corrected below.

Column 1, line 13, for "mucles" read —muscles—; column 2, lines 50 to 55, in the table, second column thereof, the first three compounds should be in the upper bracket and the "1-hexyl" compound should be bracketed with "The new alkyl radical compounds"; column 3, lines 23 to 25, the formula should appear as shown below instead of as in the patent:

lines 46 to 48, for that portion of the formula reading

column 4, lines 55 to 57, the formula should appear as shown below instead of as in the patent:

lines 59 to 61, the formula should appear as shown below instead of as in the patent:

same column 4, lines 73 to 75, for the right-hand portion of the formula reading

column 5, lines 26 and 27, for "(0.2 mole)" read —(.02 mole)—; line 65, for "(0.25 mole)" read —(.025 mole)—; column 6, lines 63 to 68, Example V, the formula should appear as shown below instead of as in the patent:

column 7, lines 20 to 23, for that portion of the formula reading

column 8, lines 43 to 47, Table I, the formula should appear as shown below instead of as in the patent:

column 10, line 43, the formula should read as shown below instead of as in the patent:

Signed and sealed this 12th day of April 1960.
